United States Patent Office.

DAVID HIRSCHBERG, OF BALTIMORE, MARYLAND.

Letters Patent No. 96,915, dated November 16, 1869.

IMPROVED CARPET.

The Schedule referred to in these Letters Patent and making part of the same.

To all whom it may concern:

Be it known that I, DAVID HIRSCHBERG, of the city of Baltimore, county of Baltimore, and State of Maryland, have invented a new and useful Leather Carpet; and I do hereby declare the following to be an exact description thereof, reference being had to the accompanying drawings, and to the letters of reference marked thereon, making a part of this specification, in which—

Figure 1 represents a square piece of leathier, with four holes punched through at equidistances apart.

Figure 2 represents another piece of leather, with four projections, each having a square head.

Figure 3 shows how the two pieces are attached together.

Figure 4 shows how three pieces are put together.

Figure 5 shows how four pieces are attached.

Figure 6 represents the five pieces attached together, exhibiting the mode of forming the carpet.

Figure 7 represents the under side of the square piece, fig. 1, with the heads of the other pieces, fig. 2, after having been passed through the holes of fig. 1; are firmly clinched in the centre by being pressed or stamped with a circular tool.

Figure 8 shows the pieces put together, forming a carpet of any length or width required, and in various colors.

The nature of my invention consists in the shape and construction of the two pieces, one being square, with apertures at equidistances apart, and the other with projections, having square heads on each projection, the pieces being stamped (or cut by a proper tool) out of waste-pieces of leather, of any color, so

that when put together, form a cheap, elastic, and very serviceable carpet.

To enable others skilled in the art to make and use my invention, I will proceed to describe the mode of constructing it.

With a die or tool made for the purpose, or with a common knife or scissors, I first cut the square piece (fig. 1) of leather, and punch four holes, A A, through it, and, for the sake of economy, I can use small scraps or pieces of waste-leather, if I think proper.

Each piece is cut three-quarters of an inch square, more or less. I then cut another piece of leather, somewhat rounding, as seen at fig. 2, with projections B B, each projection B having a square head, C.

I force four of these heads C through the four apertures A A, and then clinch them or press them together on the under side of the square piece, as shown at fig. 7, each piece being stamped or cut about three-quarters of an inch in size, more or less.

The pieces can be put together by children, and by hand, and a cheap and durable carpet can be made, of any required dimensions.

What I claim as my invention, and desire to secure by Letters Patent, is—

The construction of the two pieces of leather, figs. 1 and 2, by which a carpet is made, of any size or dimensions, and of any color or appropriate pattern, as herein described.

DAVID HIRSCHBERG.
